UNITED STATES PATENT OFFICE.

JOHN HUGH ALEXANDER MCPHEE, OF DUNEDIN, NEW ZEALAND.

TOBACCO CUTTER AND BOX.

No. 888,642.

Specification of Letters Patent.

Patented May 26, 1908.

Application filed December 29, 1906. Serial No. 349,984.

To all whom it may concern:

Be it known that I, JOHN HUGH ALEXANDER MCPHEE, of Dunedin, New Zealand, have invented certain new and useful Improvements in Tobacco Cutters and Boxes, of which the following is a specification.

My invention is for a tobacco cutter and box which can be carried in a pocket of the user, and which comprises cutting means combined with a box for the cut tobacco having also a compartment for matches.

The leading feature of my invention is the cutting means combined with a box or receptacle for the cut tobacco.

The principal cutting means consist of a blade of peculiar construction projecting from the tobacco receptacle, the tobacco being shaved through a slot cut in the bottom of the top off a plug and the shavings passing upwards through the slot into the box the arrangement being thus similar to an ordinary carpenter's plane.

Subsidiary cutting means consist of a blade fitted to the lid of the box coöperating with a blade fitted to the side of the box, for the purpose of cutting a piece of tobacco too small to be cut by shaving.

My invention consists of these features and of the features and combination and arrangement of parts hereinafter described and more particularly pointed out in the claims.

In the accompanying drawings illustrating my invention similar numerals of reference indicate similar parts and Figure 1 is a side view of my invention. Fig. 2 is a plan view. Fig. 3 is an end view.

The box (1) is divided by a partition (2) into two compartments, one (3) to hold tobacco, and the other (4) to hold matches.

A hinged lid (5) is provided for the match compartment adapted to be held in position when shut by a flat spring (6) or other well known device for the purpose. The tobacco compartment (3) has a curved lid (8) which is similarly held in position when closed by a flat spring (7) and is fitted at one side with a cutting blade (9) and provided with a thumb-loop (10) of cord or the like. The compart-

ment (3) has a blade (11) fitted to one side at the top and adapted to coöperate with the blade (9) for cutting tobacco remnants as hereinafter described. The bottom (12) of the tobacco compartment (3) has a transverse slot (13) in it through which projects the cutting edge of a blade (14) mounted on an inclined seat (15) preferably formed integral with the bottom of the box, the blade being adjustable thereon by means of a screw (16) passing through a longitudinal slot (17) in the blade.

In operation the box with lids closed is grasped firmly by one hand, a plug of tobacco is held in the other hand and the tobacco is shaved off the plug as in planing, the shavings entering the compartment (3) through the slot (13). When the plug is shaved to a size too small for the planing operation to be continued the box is grasped in the palm of the hand with the fingers; the thumb is passed through the loop (10) and the remnant of the plug is cut into pieces by the blade (9) coöperating with the blade (11) the pieces falling into the compartment (3).

Having now described my invention, what I claim as new and desire to secure by Letters Patent is:—

A tobacco cutter and box comprising a box having a flat bottom with its ends curved upwardly, said bottom having a transverse slot therein, an inclined seat on the bottom, a knife adjustably held on said seat, and having its cutting edge projecting through the slot, said box having a rounded front end and a rounded upper rear corner, a hinged cover, a knife carried by one edge of the cover, a knife carried by one edge of the box and adapted to co-act with the knife on the cover, and a loop on the cover.

In testimony whereof I have signed my name to this specification in the presence of two subscribing witnesses.

JOHN HUGH ALEXANDER MCPHEE.
